UNITED STATES PATENT OFFICE.

ALFRED H. DYSON, OF MONTCLAIR, NEW JERSEY, ASSIGNOR TO KELLOGG SWITCHBOARD & SUPPLY COMPANY, OF CHICAGO, ILLINOIS, A CORPORATION OF ILLINOIS.

TELEPHONE SYSTEM.

1,289,704.

Specification of Letters Patent. Patented Dec. 31, 1918.

Application filed March 14, 1917. Serial No. 154,661.

To all whom it may concern:

Be it known that I, ALFRED H. DYSON, a citizen of the United States of America, residing in Montclair, county of Essex, and 5 State of New Jersey, have invented certain new and useful Improvements in Telephone Systems, of which the following is a specification.

My invention relates to telephone systems 10 and more particularly to systems in which pay station devices are provided of a type requiring the subscriber to deposit a coin or token in the pay station associated with his instrument in order to place his substation in position to make a call. I provide means 15 by which the coin or token is returned to the subscriber in case a connection is not obtained and means by which the coin or token is deposited in a receptacle at the substation in case a connection is obtained.

The object of my invention is to secure a 20 superior arrangement to the arrangements of this general nature heretofore known in the art. I accomplish this object by reversing the flow of current over the calling line when the called party answers to actuate mechanism to collect the suspended coin. This reversal of current may also be used for supervisory purposes.

30 In accordance with my invention, I provide an arrangement at the subscriber's station requiring the subscriber to deposit a coin before sending in his call. In case a connection is obtained, the answering subscriber by his act of answering the call, ordinarily by the removal of his telephone from its hook, reverses the current over the calling line thus actuating mechanism which deposits the coin in the receptacle provided 35 for it. In case a connection is not obtained the calling subscriber, by placing his telephone upon its hook, causes the coin to be returned to himself.

The present application is a continuation 40 in part of my application for Letters Patent, Serial No. 270,492, filed July 20, 1905.

Referring to the drawings, Figure 1 is an 45 illustration of the machine switch of my invention.

50 Fig. 1^a, Fig. 1^b, Fig. 1^c, Fig. 1^d, Fig. 1^e and Fig. 1^f illustrate details of the switch shown in Fig. 1.

Fig. 2 illustrates in diagrammatic form a 55 subscriber's telephone line extending from a substation to the exchange and there con-

nected to an automatic switch with which is shown associated the circuits of a first selector.

Fig. 3 illustrates similarly the circuits of a second selector and a battery control circuit. 60

Fig. 4 illustrates similarly the circuits of a connector and a second telephone line provided with its automatic switch.

Fig. 5 illustrates circuits of a second selector and a battery control circuit different from that of Fig. 3. 65

Fig. 6 illustrates a trunk circuit and a battery control circuit adapted to be used in trunking between exchanges. 70

Fig. 7 illustrates a substation equipped with pay station apparatus.

Referring first to Fig. 1, the switch there shown is adapted to be operated by means of escapement movements; shaft 1, when 75 the switch is in its idle or normal position, having a tendency to revolve, due to its being attached to motor-spring 37. Upon the lower portion of shaft 1 are rigidly mounted thirty wipers in sets of three, A⁰, 80 A⁰, A⁸, etc.; B⁰, B⁸, etc.; C⁰, C⁸, etc.; those having the same co-efficient constituting a set. These wipers are insulated from each other and are disposed radially by sets, with respect to the shaft. Adapted to be engaged 85 by these wipers are thirty sets, or curved rows, of immovable contacts, of which a sectional view is shown in Fig. 1, each row being provided with a common strip extending beneath and parallel to it. The said 90 contacts are mounted in three banks in vertical and horizontally curved rows.

A top view of the wipers and contact banks is shown in Fig. 1^f, a being the common terminal. When shaft 1 is caused to 95 rotate from left to right, wiper A⁰ passes over the horizontal curved row of contacts a⁰. When the said wiper has revolved a distance such that it assumes the position of wiper A⁸, as shown in Fig. 1^f, wiper A¹ 100 is in a position, with respect to the vertical edge of the contact bank, similar to that of wiper A⁰, shown in the illustration. The shaft continuing to revolve, wiper A¹ passes over the lowest curved row of contact points 105 a¹. When the said wiper has passed over the last of said contact points, the shaft continuing to revolve, wiper A² engages the first contact at the left of row a²; and when the said wiper has left the row, wiper A³ 110

begins passing over the contacts of its appropriate row. It will be seen that one complete revolution of the shaft 1 will cause each immovable contact of a bank to be wiped by its appropriate wiper. Wipers B^o, B^o, etc., C^o, C^o, etc., operate co-incidentally with wipers A^o, A^o, etc., with respect to their appropriate contact banks.

In accordance with my invention, in operating the switch, a number of primary rotary movements of the shaft are allowed, depending upon the level of immovable contacts with which it is desired to connect. Each of these first movements is sufficient to move a set of wipers entirely across its respective rows of contacts. When the desired set of wipers is, in this manner, brought, with respect to its contact banks, to a position corresponding to that of wiper A^o, as shown in Fig. 1°, a number of secondary rotary movements of the shaft in the same direction are allowed, to move the said desired set of wipers from contact to contact of its rows, each movement causing the wipers to close contact between successive contacts and their commons, the movement of the wipers being arrested when the proper contacts are engaged by them.

To secure the return of the switch to normal, the shaft is allowed to complete the revolution upon which it has been started, its movement being arrested as soon as the revolution is completed. Upon such completion, apparatus is automatically brought into play to cause spring 37 to be wound up, preparatory for a further use of the switch. It will be noted that each time the switch is operated and returned to normal, each contact in the different banks is wiped by its appropriate wiper, and this is believed to be a new and valuable feature of a switch of this character, inasmuch as the accumulation of dust upon contacts and wipers is prevented and they, themselves, kept, at all times, bright and clean.

The movements of the shaft are controlled in the following manner, reference being had to Fig. 1: One or more impulses of current are first caused to flow through magnet 8, depending upon the contact levels to be selected. Each impulse of current causes the attraction and release of armature 9. Mounted upon shaft 1 is a disk 4, having a single tooth in its periphery which, as shown in the illustration, is engaged by detent 15, preventing the movement of the shaft. Arm 10 mounted upon armature 9 (the end of which is illustrated as broken) extends downward so as to overlap arm 14 mounted upon armature 12, its lower end being on a level with the lower end of arm 14, this being shown complete in Fig. 1^c. The first attraction of armature 9 causes arm 10 to press against the projection shown upon detent 15, causing the said detent to

move out of engagement with the tooth upon disk 4, so that the detent no longer restrains movement of shaft 1. Mounted upon armature 9 is detent 5 which, upon the attraction of the armature, presses against the circumference of circular ratchet wheel 2 rigidly attached to shaft 1, arresting movement of the shaft when it has rotated the distance from one tooth of ratchet wheel 2 to the next by engaging said next tooth. Successive attractions and releases of armature 9 permit movements as described, and the extent of these movements is so gaged as to bring successive sets of wipers to positions in front of, but not engaging, the first contacts of their respective levels.

Fig. 1^d is a top view of ratchet wheel 2, detent 5 being shown in the normal position.

3 is a second ratchet wheel rigidly attached to shaft 1, its teeth being so spaced that successive movements, as determined thereby, allows movements of the wipers from contact to contact only. Normally engaging the said ratchet wheel 3, is detent 7, having upon it a projection adapted to be engaged by arm 10 upon armature 9 with each attraction of the said armature, and moved out of engagement with ratchet wheel 3 and so held as long as the armature 9 is attracted. With each release of armature 9, detent 7 engages a tooth of wheel 3 and arrests rotation of the shaft.

The rows having been selected in the manner described, one or more impulses of current are now caused to flow through magnet 11, depending upon the proper contacts in the rows. Each impulse causes the attraction and release of armature 12 which controls detent 6 in a manner generally similar to that in which detent 5 is controlled by magnet 8, the shaft being permitted to rotate one step for each impulse. Detent 7, with each energization of magnet 11, is caused to release ratchet wheel 3 by the operation of arm 13; and upon the de-energization of the magnet, again engages the wheel, preventing movement of shaft 1.

Fig. 1^e is another view of the arrangement of these parts. Upon armature 12 of magnet 11, is shown arm 14, adapted to cause the retraction of detent 15, should the detent be in its normal position at the time magnet 11 is energized. This is necessary to enable wipers A^o, B^o, and C^o to be controlled by magnet 11 in a from-contact-to-contact movement, inasmuch as a complete revolution of the shaft is required to bring the said wipers into positions where they may be controlled by magnet 11. In other words, ten impulses of current are sent through magnet 8 to bring the zero wipers into operative position, thus constituting a complete revolution and causing engagement of disk 4 by detent 15.

Referring now to Fig. 1, when magnet 16 is energized, pawl 21, pivotally associated with its armature 20, moves downward, engaging the next tooth of ratchet wheel 26. When the magnet is deenergized, armature 20 is retracted and pawl 21 moves in a vertical direction, causing ratchet wheel 26 to revolve one step from left to right. The said ratchet wheel is rigidly attached to ratchet wheel 27, moving the latter with it, and the end of lever 27^a is moved out of engagement with the tooth of ratchet wheel 27, previously engaged by it, and rests upon the periphery of the wheel. The said lever being mechanically connected to circuit changing spring 29 as shown, this movement causes the said spring to disengage spring 28 and to engage spring 30. Lever 27^a may be mechanically attached to, 20 and cause simultaneous movements of, a plurality of circuit changing springs.

When magnet 22 is energized, its armature 23 is attracted. Pivotally associated with the said armature is pawl 24, engaging a tooth of ratchet wheel 26, the pawl upon the attraction of armature 23 moving toward the left, revolving ratchet wheel 26 one step and thereby moving ratchet wheel 27 into such a position that lever 27^a again 30 engages with its end a tooth of ratchet wheel 27, adjacent to that from engagement with which it was moved by the above-described operation of pawl 21. This operates to move the circuit changing spring 29 out of engagement with spring 30 and again into engagement with spring 28, its normal position.

The attraction of armature 23 also moved arm 25 toward the left in such manner that an orifice toward its projecting end is caused 40 to slip over and engage the pin shown in the illustration upon detent 7. In Fig. 1^b, a top view of these parts is shown. When magnet 22 is deenergized, arm 25 is moved toward the right by the return of armature 23, 45 and reference to Fig. 1^b makes clear the manner in which this movement of arm 25 moves detent 7 out of engagement with ratchet wheel 3.

The disengagement of detent 7 in the manner described operates to restore the wipers to normal by allowing a free rotation of the shaft, until detent 15 engages the single tooth of disk 4.

Referring to Fig. 1, 31 illustrates (viewing it from in front) an arm of considerable length, extending from the rear of the switch and engaging, with one edge, a disk fastened to shaft 1 at all times. When the shaft is in its normal position, as shown in Fig. 1, the edge of arm 31 engages a depression or flattened portion 31^a in the periphery of disk 31^b, as shown in Fig. 1^c, and, in this position the arm 31 engaging the projection shown upon arm 25, holds the 55 said arm above the pin on detent 7. With

the first rotary movement of the shaft, the edge of arm 31 disengages the depression mentioned, and rests upon the periphery of the shaft; its end, under these circumstances, being moved to the right so that it no longer 70 supports arm 25 in the position shown in Fig. 1. It is retained thus retracted until the shaft has completed one revolution. When this occurs, its edge again engages the depression in shaft 1 before mentioned, its 75 end moves forward and lifts arm 25 out of engagement with detent 7 in which it was placed to release the switch, so that the said detent again engages ratchet wheel 3. This, it will be noted, occurs at the termination 80 of the release operation before described and simultaneously with the engagement of detent 15 with disk 4, detent 7 being thereby returned to normal and ready to perform its usual function upon the next operation of 85 the switch.

The means by which spring 37 is wound up after the return of the wipers to normal will now be described. The details of the mechanism used for this purpose are shown 90 in detail in Fig. 1^a. Attached to the upper portion of shaft 1, is cam 36 having an off-set, as shown in Fig. 1^a, normally engaged by pawl 38. As the shaft is revolved, cam 36 gradually moves pawl 38 to the left; 95 and when the shaft approaches the completion of its revolution, pawl 39, attached to and moving with pawl 38, engages a tooth of ratchet wheel 41 adjacent to that previously engaged by it. As soon as the revolution of the shaft is completed, pawl 38 engages the off-set in cam 36, its free end moving toward the center of the shaft and retracting pawl 39 to move ratchet 41 one step from left to right. Ratchet 40 is rigidly 100 attached to ratchet 41 and moves with the latter, the end of spring 43 (see Fig. 1^a) being moved out of its engagement with a tooth of ratchet 40, which is its normal position, in such a manner that it rests upon 105 the periphery of the said ratchet. Spring 43 is thereby caused to engage spring 42, and this closes circuit through winding magnet 32. The said magnet is arranged in a vibratory circuit, a novel form of circuit breaker 110 being provided consisting of disk 46 (see Fig. 1^a) and its associated parts. This circuit breaker is designed to secure a full stroke of the armature of magnet 32 before the magnet's circuit is broken, and operates 115 in the following manner: The energizing circuit of magnet 32 passes through contact 47-48. Upon disk 46 is provided a depression 46^a engaged by one end of armature 33, and a second depression 46^b adapted to be engaged by lever 46^c. When armature 33 is 120 attracted, its end, engaging depression 46^a, moves upward, and as the full stroke of the armature is completed, it impacts upon the upper edge of depression 46^b. This 125 130

causes a slight rotary movement of disk 46 from left to right, and lever 46^c is thereby caused to move out of the position shown in the illustration into depression 46^b, breaking the circuit of magnet 32 by opening contact through springs 47 and 48. Magnet 32 is thereby deenergized, and its armature is retracted by spring 33^b to the position shown, the end of the armature engaging the lower edge of orifice 46^a and moving disk 46 a short distance from right to left so that lever 46^c again rests upon the periphery of the disk, reestablishing contact between springs 47 and 48, and causing another energization of the magnet.

Each attraction and release of armature 33 of magnet 32 causes ratchet 34 to be revolved a step from left to right by means of pawl 33^a, the said ratchet moving independently of shaft 1, and the shaft remaining motionless under these conditions. One end of spring 37 is attached to ratchet 34 and the movement of freely moving ratchet 34 is in the same direction as the movement of the shaft when the switch is operated. This movement of ratchet 34, therefore, operates to wind up the said spring.

Mounted upon ratchet 34 is cam 35 (Fig. 1), its shape being similar to that of cam 36, being provided with an off-set normally engaged by pawl 38. The described winding movement of ratchet 34 moving cam 35 with it, gradually moves pawl 38 to the left; and when ratchet 34 approaches the completion of its revolution, pawl 38 causes pawl 39 to engage the next tooth of ratchet 41. When armature 33 has been vibrated a sufficient number of times to cause a complete revolution of ratchet 34, cam 35 will also have made a complete revolution and pawl 38 again engages its off-set. Pawl 39 then moves to the right and effects a rotary movement of ratchet 41 one step from left to right. It will be noted that this is the second movement of ratchet 41 accomplished in the winding operation, and this second movement operates to bring ratchet 40 in such a position that spring 43 moves from the periphery of the ratchet into engagement with the tooth next to that engaged by it before the winding operation commenced. This engagement causes spring 43 to disengage spring 42 and opens the circuit of magnet 32, preventing further operation of the said magnet.

All operating parts of the switch have now been returned to normal, and energy has been stored for operating the switch a second time.

While I have especially designed the switch, shown in Fig. 1, for use in connection with the circuit arrangements shown at the right of Fig. 2, at the left of Fig. 3, at the left of Fig. 5, at the right of Fig. 6, and with minor changes in connection with the circuit arrangement shown at the left of Fig.

4, the invention of the latter figures is not necessarily confined to the operation of such a machine as I show in Fig. 1. Fig. 1 is generically illustrative of forms of mechanical movements which different parts of the circuit arrangements, comprised in my invention, may assume. For purposes of reference, I shall designate, by descriptive terms, the principal magnets illustrated in Fig. 1. When, in the description of the circuit drawings, I come to an electromagnet whose work may assume a form similar to that accomplished by a magnet of Fig. 1, I shall designate it by the descriptive title.

A magnet, having functions similar to magnet 8, may be called a "primary magnet."

A magnet, having functions similar to magnet 11, may be referred to as a "secondary magnet."

A magnet, having functions similar to magnet 16, may be referred to as a "circuit-changing switch magnet."

A magnet, having functions similar to magnet 22, may be referred to as a "release magnet."

Referring to the circuit arrangements, Figs. 2, 3 and 4 placed in the order named with Fig. 2 at the left constitute a first complete diagram illustrative of the circuits of the telephone system of my invention. The apparatus included in this single diagram is that necessary for establishing connection between two subscribers' lines. In Fig. 2, I have illustrated a substation A, including a pair of keys 60 and 61 adapted to be used by the subscriber for grounding limbs P and S, respectively, of the telephone line at will. A key 62 is also provided, enabling the subscriber to open the metallic circuit of the substation. Limbs P and S extend to the central office and are there connected with an automatic switch individual to the line, which may be called a private switch.

The system, which I have shown in the diagram referred to, may be used to accommodate several thousand subscribers. Each subscriber's line is provided with an automatic switch, having circuits similar to those illustrated in Fig. 2, and these switches may be conveniently divided into groups of one hundred, each switch including movable switch arms or wipers such as are designated 82, 98 and 97 in Fig. 2, together with a plurality of contacts constituting the multiplied terminals of first selector switches. These contacts may conveniently be disposed in three curved rows, one above the other; those of the upper row, among which contact 80 would be included, being disposed in such a manner that successive terminal contacts alternate with permanently grounded contacts, such as contact 81. Each row or level of contacts is provided with a common strip, such as I have shown at 79, 100^a and 130

99^a in Fig. 2. These common strips are the true terminals of the circuits of the private switch, wipers 82, 98 and 97 having themselves no circuit connections, but being arranged so that when the switch is operated, they close circuits between the common strips and the contacts before mentioned.

The number of first selector switches, assigned to a group of one hundred private switches, may vary, depending upon the number of calls which may be expected to co-exist from the lines of the group. Ten first selector switches for a group of one hundred private switches would be sufficient 15 in an ordinarily busy exchange.

A first selector switch, circuits of which I have illustrated at the right of Fig. 2, is common for connection to all subscribers in the exchange.

20 At the left of Fig. 3, I have illustrated the circuits of a second selector switch, such a switch being common for connection to a group of one thousand subscribers' lines.

At the left of Fig. 4, I have illustrated 25 the circuits of a connector switch, such a switch being common for connection to a group of one hundred subscribers' lines.

Generally speaking, a calling subscriber first connects his telephone line through to a 30 first selector switch by operating his private switch. He thereupon operates the first selector switch in such manner that it connects his line through to a second selector switch assigned to the one thousand line 35 group of subscribers' lines, among which is included the line of the subscriber whom he is calling. The subscriber then operates the second selector switch in such manner that it connects his line through to a connector switch adapted to be operated to connect his line directly to any line of a one hundred line group of the aforementioned one thousand line group, among which is the line of the desired subscriber. He then 40 operates the connector switch to connect his line through to the desired subscriber's line. The system operates as a multiple trunk system, the principles of which are well known in the art.

50 Referring to the complete diagram before mentioned, and assuming that subscriber A desires to connect his line with the line of subscriber B, whose number is assumed to be 3456, the operation of the system is as follows: Subscriber A first removes the receiver from the switch hook, closing contact 73-72 and establishing a flow of current as follows: from ground at the central office, through contact 67-68, through contact 55 69-70, over limb S of the line, returning over limb P, through contact 63-64, through the winding of relay 66 to battery 74, energizing relay 66, which attracts its armatures. This attraction causes a flow of 60 current from ground, through contact 86-

87, through contact 76-75, through the winding of magnet 90, contact 91-92, to battery 74. Magnet 90 is placed in a vibratory circuit and will alternately be energized and deenergized as long as relay 66 70 is maintained energized, due to contact 76-75 being closed. Each energization and deenergization of magnet 90 causes shaft 96 to rotate a step, carrying with it rigidly attached wipers 82, 98 and 97. The first 75 movement of the shaft brings wiper 82 out of engagement with a contact, a multiplied terminal of the first selector switch last used by subscriber A in establishing a connection, and into engagement with a permanently grounded contact such as 81. Current thereupon flows from ground, through said contact, through wiper 82, through common strip 79, through contact 83-84, through contact 77-78, through the winding of relay 66 to battery 74, locking the said relay and preventing its deenergization by the opening of contact 67-68 which occurs as the relay becomes energized.

The second energization and deenergization of magnet 90 brings wiper 82 into engagement with a contact, the terminal of a first selector switch. Should this switch be already in use, current continues flowing through relay 66 maintaining it energized, 95 the path being traced as follows: from ground, through relay 89 of the private switch then connected with a multiplied terminal of the first selector switch, through contact 85-83 of the said private switch, 100 through the common strip of the said switch, its wiper 82, a contact, a multiple of the one which wiper 82 of the private switch of subscriber A just engaged, through the contact engaged by the said wiper to the 105 common strip of the private switch of subscriber A, through contact 83-84 of the said switch, through contact 77-78, through the winding of relay 66 to battery 74. The windings of relays 66 and 89 are 110 so proportioned that this flow of current is not of sufficient volume to cause relay 89 to attract its armature. A third energization and deenergization of magnet 90 again brings wiper 82 into engagement with a permanently grounded contact, and a fourth energization and deenergization of the said magnet brings wiper 82 again into engagement with a contact, a terminal of a first selector switch. Assuming that the contact 115 thus engaged is contact 80 of the first selector switch illustrated in Fig. 2, and that the said switch is idle, circuit through relay 66 is broken, due to the fact that contact 80 is insulated from ground, as appears upon 120 an inspection of Fig. 2, in which the first selector switch is shown in its idle position. Relay 66 becomes deenergized, the retraction of its armature opening the circuit of magnet 90 at contact 76-75, thereby arrest- 125 130

ing wipers 82, 98 and 97 in engagement with contacts 80, 100 and 99, respectively.

When relay 66 was first energized, it prepared for the movement of arms 83, 246, 5 63 and 70 into engagement, respectively, with contact points 85, 246^a, 65 and 71; and upon its deenergization, caused the engagement of the said arms with the said contact points. A reference to magnet 16, illustrated in Fig. 1, and the method of operation of the said magnet in connection with ratchet 27, discloses a convenient mechanical combination by which the aforesaid movement may be effected.

15 The engagement of contact point 85 by arm 83 put ground on contact 80 of the first selector switch and its multiples, through relay 89, rendering the said switch busy with respect to other private switches having access to it. The engagement of arm 246 with contact point 246^a rendered the private switch of subscriber A busy with respect to other subscribers establishing connection with his line. The engagement of arms 63 20 and 70 with contact points 65 and 71, respectively, extended the limbs of the line of subscriber A through to the circuits of the first selector switch, thereby rendering the said switch controllable by subscriber A 25 from the substation.

Subscriber A, by means of key 60, now grounds limb P of the line a number of times, corresponding to the thousands digit of the called subscriber's number, or three 30 times, causing three impulses of current to flow from ground at the substation, over limb P of the line, through contact 63—65, through common strip 100^a of his private switch, through wiper 98 to contact 100, 35 through contact 101—102, through the winding of primary relay 104 to battery 74.

Each impulse of current causes an energization and deenergization of primary relay 104, which attracts and releases its armature three times and causes three impulses of current to flow from ground at the first selector switch, through contact 108—109, 40 through contact 106—105, through the winding of primary magnet 114 to battery 74. 45 The resulting energizations of the primary magnet 114 causes three primary rotary movements of shaft 132. The third movement brings wipers 129, 133 and 136 to positions adjacent to, but not engaging, the first contacts of three horizontal rows of contacts, multiplied terminals of second selector switches assigned to the third one thousand line group of subscribers' lines, or a group including lines of subscribers to 50 whom are assigned numbers from 3,000 to 3,999.

Subscriber A now sends, by key 61, one impulse of current from ground at the substation, over limb S of the telephone line, 55 through contact 70—71, through contact

99^a—97—99, through contact 115—116, through the winding of secondary relay 118 to battery 74, causing a single attraction and release of the relay's armature and a flow of current from ground, through contact 119—120, through the winding of circuit-changing switch magnet 111 to battery 74. This causes the energization of the said magnet and the attraction of its armatures. The attraction of armature 108 causes a flow 75 of current from ground, through contact 108—110, through the winding of secondary magnet 122 to battery 74. The latter magnet is arranged in a vibratory circuit. Its first energization and deenergization operates to move wipers 129, 133 and 136 into engagement with the first contacts of the rows described. In case these are terminals of a second selector switch already in use, circuit-changing switch magnet 111 is 80 maintained energized by a flow of current from ground at the first selector switch then connected with the said second selector switch, through relay 139 of said first selector switch, through its contact 128—126, 85 through its common strip 131; its wiper 129, a multiple of the contact engaged, to the said contact, through wiper 129 of first selector switch, Fig. 2, to common strip 131, through contact 126—127, through contact 113—112, 90 through the winding of magnet 111, to battery 74. The windings of relay 139 and 111 are so proportioned that this flow of current is not of sufficient volume to cause relay 139 to attract its armature. It is apparent that secondary magnet 122 will continue to vibrate, causing with each energization and deenergization a secondary movement of shaft 132, carrying with it 95 wipers 129, 133 and 136 as long as magnet 100 111 continues energized. When wipers 129, 133 and 136 engage contacts, terminals of an idle second selector switch, which is assumed to occur when they engage contacts 130, 134 and 137, terminals of second selector switch, Fig. 3, contact 130 is insulated 110 from ground and the flow of current through magnet 111 is interrupted. Its armatures thereupon resume their normal positions shown in the illustration, breaking contact 115 108—110 and preventing further operation of secondary magnet 122. Wipers 129, 133 and 136 are thus brought to rest in engagement with contacts 130, 134 and 137. The deenergization of circuit-changing switch magnet 111 also moved arms 126, 102 and 115, respectively, into engagement with contacts 128, 103 and 117, respectively. The closure of contact 126—128 put ground through relay 139, through contact 128—126, contact 125 131—129—130, to the multiples of contact 130, rendering the second selector switch busy with respect to other first selector switches having access to it. The closing of contacts 101—103 and 115—117 extended 130

limbs P and S of the telephone line through to the circuits of the second selector switch, Fig. 3, and rendered the said switch controllable from substation A.

- 5 Subscriber A now grounds limb P of his line a number of times, corresponding to the hundreds digit of the called subscriber's number, or four times, causing four impulses of current to flow from ground at the substation, over limb P, through contact 142—143 of second selector switch, Fig. 3, through the winding of primary relay 145 to battery 149. These impulses cause the armature of the said relay to be attracted and released four times and four impulses of current to flow from ground at the second selector switch, through contact 150—151, through contact 148—147, through the winding of primary magnet 153 to battery 149.
- 10 20 Each impulse through magnet 153 causes a primary movement of shaft 168, carrying with it wipers 165, 169 and 172. The fourth of these movements brings the wipers to positions adjacent to, but not engaging, rows 25 of contacts, multiplied terminals of connector switches assigned to a group of lines including subscribers' lines which are assigned numbers from 400 to 499 of the selected one thousand.
- 20 30 Subscriber A now causes a single impulse of current to flow from ground at the substation, over limb S of the line, through contact 204—205 of the second selector switch, through secondary relay 207 to battery 149, causing a single attraction and release of the relay's armature, and an impulse of current to flow from ground at the second selector switch, through contact 210—209, through the winding of circuit-changing switch magnet 154 to battery 149. The consequent attraction of the magnet's armatures established a flow of current from ground, through contact 150—152, through the winding of secondary magnet 157 to battery 149.
- 35 40 45 Magnet 157 is placed in a vibratory circuit and will alternately be energized and deenergized until contact 150—152 is broken. Each energization and deenergization of magnet 157 causes a secondary rotary movement of shaft 168, moving wipers 165, 169 and 172 to successive sets of contacts, terminals of connector switches of the described group, until terminals of an idle switch are reached. In case contacts of the rows, engaged by wipers 165, 169 and 172, are terminals of a busy connector switch, magnet 154 is maintained energized by flow of current from ground at the second selector switch then connected with the said connector switch, through relay 175, contact 162—164, contact 167—165 of the second selector switch referred to, to a multiple of the contact engaged by wiper 165 of Fig. 3, to said contact, to common strip 167 of the second selector switch now being operated,
- 50 55 60 65 70 75 80 85 90 95 100 105 110 115 120 125 130 through its contact 162—163, through contact 156—155 through the winding of magnet 154 to battery 149. Such flow of current is of insufficient volume to cause relay 175 to attract its armature. When a contact terminal of an idle connector switch is reached by wiper 165, such contact will be insulated from ground and circuit through magnet 154 will be interrupted, deenergizing it and thereby allowing the return of its armature to normal and preventing further energizations and deenergizations of secondary magnet 157; wipers 165, 169 and 172 resting in engagement, respectively, with contacts 166, 170 and 173, assumed to be terminals of a trunk line extending to the selected connector switch shown in Fig. 4. The deenergization of circuit-changing switch magnet 154, above mentioned, also caused arms 162, 142 and 204 to move into engagement with contacts 164, 144 and 206, respectively. The closing of contact 162—164 put ground to contact 166 and its multiples, rendering the said connector switch busy with respect to other second selector switches having access to it. The closing of contact 142—144 and contact 204—206 extended limbs P and S of the telephone line of subscriber A through to the circuits of the connector switch shown in Fig. 4, rendering the said switch controllable from substation A.
- 135 Subscriber A now causes five impulses to flow from ground at the substation, through contact 171—169—170, contact 178—179, contact 181—182, contact 184—185, and through the winding of primary relay 188 of the connector switch. Five attractions and releases of said relay's armature are caused thereby, resulting in five impulses of current over the following path: from ground at the connector switch, through contact 192—191, through contact 195—194, through contact 198—199, through the winding of primary magnet 202 to battery 203. Each energization of primary magnet 202 effects a primary rotary movement of shaft 239, carrying with it wipers 236, 240 and 243. The fifth movement brings the wipers adjacent to rows of contacts, multiplied terminals of the lines of subscribers to whom are assigned numbers from 3451 to 3460.
- 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

engagement with contacts 226, 200, 186, 219 and 230, respectively. The engagement of arm 198 with contact 200 places secondary magnet 233 under control of primary relay 188. Six impulses of current are now caused by subscriber A to flow from ground at the substation, through contact 184—186 and primary relay 188, Fig. 4, to battery 189. Each of the six attractions and releases of the relay's armature causes a flow of current from ground, through contact 192—191, through contact 193—194, through contact 198—200, through the winding of secondary magnet 233 to battery 203. Each energization and deenergization of the said secondary magnet causes wipers 236, 240 and 243 to move to engage successive contacts of the rows above-mentioned, the sixth movement bringing the wipers into engagement, respectively, with contacts 237, 241 and 244, multipled terminals connected to the private switch of subscriber B, or subscriber 3456. Subscriber A now causes one impulse of current to flow from ground at the substation, through contact 217—219 of the connector switch, through relay 221 to battery 189, causing circuit-changing switch magnet 193 to be energized by establishing a flow of current over the path previously traced.

Assuming first that the line of the called subscriber is busy, contact 237 in this case is characterized by a ground connection; and upon the attraction of armature 196 of magnet 193, closing contact 196—197, a flow of current results from grounded contact 237, through wiper 236, through common strip 238, through contact 224—226, contact 197—196, through the winding of release magnet 232 to battery 189, energizing magnet 232. When the impulse through relay 221 ceases, causing the deenergization of circuit-changing switch magnet 193, the latter's armature 196 disengages anvil 197, opening circuit through release magnet 232, causing its deenergization and the consequent return of the connector switch to normal; wipers 236, 240 and 243 disengaging contacts 237, 241 and 244, and arms 224, 198, etc., returning to their normal engagement with contacts 225, 199, etc.

When the connector switch returns to normal, contact 235—234 is closed and the calling subscriber receives the busy signal from machine 263 in his receiver, notifying him that the line called is busy. He thereupon simultaneously presses keys 60 and 61 and replaces his receiver. Relays 188 and 221 of the connector switch, Fig. 4, are simultaneously energized, closing contact 190—222, establishing a path for the flow of current as follows: from ground at second selector switch, Fig. 3, through release relay 175, through contact 164—162, through contact 167—165—166, through contact 251—250

(Fig. 3) through contact 190—222 (Fig. 4) through the winding of release magnet 232 to the active side of battery 189. This flow of current energizes release relay 175 of Fig. 3, and release magnet 232 of Fig. 4. The energization of release relay 175 operates to prepare the second selector switch, Fig. 3, first selector switch, Fig. 2, and private switch, Fig. 2, for their returns to normal, which will occur as soon as subscriber A releases keys 60 and 61, thereby removing ground from the limbs of the line, which causes the deenergization of relays 188 and 221 of Fig. 4, and the opening of contact 222—190. The opening of this contact causes the deenergization of release relay 175. The detailed description of the manner in which release relay 175 operates in connection with the returns to normal of the various switches will be hereinafter given.

In case the line of subscriber B is idle, contact 237 is connected to battery through relay 266, and release magnet 232 does not become energized upon the closure of contact 196—197. In this case, the energization and deenergization of circuit changing switch magnet 193 operates to move arms 224, 198, 184, 217 and 228 into engagement, respectively, with contacts 227, 201, 187, 220 and 231. The engagement of arm 224 with contact 227 places ground upon contact 237 and its multiples, rendering the said line of subscriber B busy with respect to other subscribers establishing connection with it. It also energizes relay 266 of the private switch which operates to cut limbs P and S of the line of subscriber B free from the circuits of the private switch. The engagement of arm 228 with contact point 231 establishes a path for the flow of current as follows: from ground at battery control circuit, Fig. 3, through the winding of relay 247, through contact 231—228 of the connector switch, through the winding of release magnet 232 to battery 189, causing the energization of relay 247. The windings of magnet 232 and relay 247 are so proportioned that this flow of current does not cause the energization of magnet 232 to a degree to cause it to attract its armature. It will be observed that the structure of Fig. 1 does not provide for a second forward movement of circuit-changing switch-members as described for arms 224, 198, 184, 217 and 228. For this purpose the well known side switch escapement movement, shown and described in Patent No. 815,321, dated March 13, 1906, to Keith *et al.* may be conveniently employed, magnet 193 controlling the forward stepping of the side switch arms, while release magnet 232 when deenergized, restores the side switch arms, all as described in the patent cited. The energization of relay 247 operates to close the following contacts: 178—180, 182—130

183, 211—213 and 214—215. A flow of current now results over the following path: from the grounded side of battery 256, through the lower winding, as illustrated, of 5 relay 255, through relay 252, energizing the said relay and attracting its armature through contact 213—211, through contact 173—172—174, over the talking circuit as shown by the heavy lines, by way of limb S 10 of the line of subscriber A, through the substation, supplying current to the transmitter for talking purposes, returning over limb P, the other side of the talking circuit through the exchange, through contact 171—169—15 170, contact 178—180, impedance coil 263, through the upper winding of relay 255, to the active side of battery 256. This flow of current does not cause relay 255 to attract its armature, the said relay being differentially 20 wound.

To cause the bell of subscriber B to be rung, subscriber A opens the path of the just-traced flow of current at his substation by means of key 62. This causes the deenergization of relay 252, its armature assumes the position shown in the illustration (Fig. 3) closing contact 253—254 and establishing a path for the flow of current from ground (Fig. 3) through contact 249—248, contact 253—254, through the winding of ringing relay 257 to battery 256. This energizes the said relay, it attracts its armatures and cuts ringing generator 258, by the said attraction, into circuit with the line of subscriber B, 30 causing his bell to ring. When subscriber A releases key 62, the talking current resumes its flow through the substation, relay 252 is again energized, the attraction of its armature breaking circuit through ringing 35 relay 257, whose armatures resume their normal positions as shown in Fig. 3.

When subscriber B answers the call by removing his receiver from the hook, contact 72—73 is closed, and a flow of current results from the grounded side of battery 256 40 (Fig. 3) through impedance 265, over the talking circuit at the exchange, as shown by the heavy lines, to limb S of the line of subscriber B, through the substation, supplying current to the transmitter, returning over limb P of the line, over the talking circuit, through impedance 264 to the active side of battery 256. The two subscribers are now in conversation through condensers 261 and 50 262, the conversational circuit being traced through the exchange by the heavily lined conductors.

When the subscribers have finished their conversation, each depresses simultaneously 55 keys 60 and 61 and replaces his receiver upon the switch hook. Assuming that subscriber B does this first, the release of the apparatus used in establishing the connection between the two subscribers is secured in the following manner: the grounding of limb S by

subscriber B short circuits the lower winding of relay 255 of Fig. 5; while the grounding of limb P maintains the flow of current through the upper winding of relay 255 from the active side of battery 256, over limb P 70 to ground at the substation. Relay 255 is differentially wound, and the flow of current through its two windings during conversation and before did not cause the attraction of armature 259. The short circuiting of 75 the lower winding as above described, current continuing to flow in the upper winding, causes the magnetization of the core of relay 255 and the attraction of its armature 259 to engage anvil 260. A flow of current 80 is thereby caused over the following path: from ground, Fig. 3, through the winding of release relay 175, through contact 164—162, through contact 167—165—166, through contact 259—260, joining the current flowing 85 from ground through relay 247, through contact 231—228, through the winding of release magnet 232 to battery 189. Relay 175 and magnet 232 are of low resistance and the above-described flow of current causes 90 the attraction of the armatures of both. The energization of release magnet 232 prepares for the return of the connector switch, Fig. 4, to normal upon the deenergization of the said magnet. The attraction of the armature 95 of the release relay 175 establishes a path for the flow of current as follows: from ground, Fig. 2, through the winding of release relay 139, through contact 128—126, through contact 131—129—130, through contact 177—176, 100 through the winding of release magnet 161 to battery 149, causing the attraction of the armatures of relay 139 and magnet 161. The attraction of the armature of magnet 161 prepares for the release of the second selector switch, Fig. 3, and its return to normal 105 upon the deenergization of the magnet. The energization of relay 139 establishes a path for the flow of current as follows: from ground at the private switch, Fig. 2, through 110 the winding of relay 89, through contact 85—83, through contact 79—82—80, through contact 141—140, through the winding of release magnet 125 to battery 74, the resulting energization of magnet 125 preparing 115 for the release of the first selector switch, Fig. 2, and its return to normal upon the deenergization of the said magnet. The energization of relay 89, which results from the above-described flow of current, causes a flow 120 of current as follows: from ground at the private switch, through contact 86—88 through the winding of relay 66 to battery 74, and the energization of the said relay.

When subscriber B releases keys 60 and 61, 125 they return to their normal positions as shown; assuming that subscriber A has not yet depressed keys 60 and 61 at his substation, relay 255 no longer attracts armature 259, and the said armature disengages anvil 130

260. This causes the deenergization of release magnet 232 of the connector switch, Fig. 4, and the return of the switch to normal. The return of arm 228 of this switch opens the circuit of relay 247 of Fig. 3. Its consequent deenergization and the release of its armatures causes arms 178, 211, 182 and 214 to return to normal. The release of the connector switch also causes relay 266 of private switch, Fig. 4, to become deenergized, restoring the private switch to normal. The deenergization of release relay 175 of the second selector switch, Fig. 3, is caused by armature 259 disengaging anvil 260. The resulting opening of contact 176-177 deenergizes release magnet 161, causing the return of the second selector switch to normal. It also causes the deenergization of release relay 139 and the opening of contact 140-141. The opening of this contact causes the deenergization of release magnet 125 and the return of the first selector switch, Fig. 2, to normal. It also causes the deenergization of relay 89 and the opening of contact 88-86. The opening of this contact causes the deenergization of relay 66 and the return of arms 83, 246, 63 and 70 to their normal positions as shown in the illustration. It is to be understood that the release of the private switch, or its return to normal, consists in the above-described operation only, wipers 82, 98 and 97 remaining in engagement with terminals of the first selector switch used. The return of arm 83 to its normal engagement with its contact 84 removes ground from contact 80 and its multiples, rendering the first selector switch, Fig. 2, idle with respect to other private switches having access to it.

Should subscriber A depress keys 60 and 61 at his substation and replace his receiver before subscriber B does so, the grounding of limb S of the line of subscriber A short circuits the lower winding of relay 255, current continuing to flow through the upper winding, over limb P, to ground at the substation. The core of the relay is thereupon magnetized, armature 259 engages anvil 260, and the release operations proceed exactly as described in the case in which subscriber B performs the release operation at his substation first.

It will be noted that during conversation, current flows through differentially wound relay 255 and in parallel paths over the lines of the two connected subscribers; that when one subscriber releases in advance of the other, current through the upper winding of relay 255 is of equal or of greater volume than that during conversation; while current through the lower winding is reduced approximately one-half, the degree depending upon the comparative resistance of the two subscribers' lines.

Should the two subscribers release simultaneously, the flow of current through the upper winding of relay 255 will be substantially the same as that existing during conversation, while the flow of current through the lower winding will be practically *nil*. 65 70

A second complete diagram, illustrative of an alternate form of the circuits of the telephone system of my invention, comprises Fig. 2, Fig. 5 and Fig. 4, placed in the order named. The method of operation of this circuit is largely the same as that of the circuit diagram already described, the difference existing in the battery control circuit, Fig. 5. The said Fig. 5 provides means whereby, upon the response of the 80 called subscriber, the direction of the flow of current in the line of subscriber A is reversed.

The description already given in connection with the previous circuit diagram applies to this second diagram to the point at which wipers 165, 169 and 172 of the second selector switch come to rest in engagement with contacts 166, 170 and 173. The impulses sent over limb P of the line, corresponding to the tens digit of the called subscriber's number, after passing through contact 171-169-170, in this case pass through contact 270-271, through contact 301-300 and through the winding of primary relay 188, operating the connector switch of Fig. 4 in the manner already described. The single impulse sent over limb S of the line after the just mentioned set of primary impulses, after passing through contact 174-172-173, passes through contact 273-274, contact 305-303 and through the winding of relay 221. The impulses corresponding to the units digit sent over limb P, and the single impulse sent over limb S thereafter, 95 100 105 traverse the above described paths.

The release of the connector switch, in case the line of the called subscriber is busy, is secured in the same manner as described in connection with the preceding diagram. 110 Should the line of subscriber B be idle, arms 224, 198, 184, 217 and 228 are caused to engage contacts 227, 201, 187, 220 and 231, as in the preceding description. The engagement of arm 228 with contact point 231 establishes a path for the flow of current from ground at battery control circuit, Fig. 5, through the winding of relay 276, causing its energization, through contact 231-228, through the winding of release magnet 232, 115 120 which, due to the resistance of relay 276, does not attract its armature, and to battery 189.

The energization of relay 276 (Fig. 5) causes the attraction of armatures 277 and 125 279, and causes arms 270, 273, 300 and 303 to engage contact points 272, 275, 302 and 304 respectively.

Current thereupon flows as follows: from the grounded side of battery 287, through the lower winding of differentially-wound relay 284, through the lower winding of relay 281, through contact 293—294, through contact 275—273, over the talking circuit at the exchange, to limb S of the line of subscriber A, through the substation, returning over limb P, over the talking circuit, through contact 270—272, through contact 296—295, through the upper winding of relay 281, through the upper winding of relay 284, to the active side of battery 287. The core of relay 284 is not magnetized by this flow of current, owing to its differential windings. The core of relay 281 is energized, attracting its armature 283 to open contact 282—283. Subscriber A opens the path of the previously traced flow of current by means of key 62, causing the deenergization of relay 281, armature 283 falling back to establish a path for the flow of current as follows: from ground, through contact 282, 283, through contact 280—279, through the winding of ringing relay 288 to the active side of battery 287. Relay 288 attracts its armatures, cutting ringing generator 289 into circuit with the called-for subscriber's line and causing his bell to ring. When subscriber A releases ringing key 62, it closes circuit through the substation, relay 281 is again energized, opening contact 282—283, deenergizing relay 288 and allowing the said relay's armatures to resume their normal positions. When subscriber B, in response to the call, removes his receiver from the hook and closes contact 73—72, an additional path for the flow of current, from battery 287, is established as follows: from the grounded side of the said battery, through the lower winding of relay 284, through winding 292 of relay 290, through contact 304—303, over the talking circuit at the exchange, to limb S of the line of subscriber B, through the substation, returning over limb P, over the talking circuit, through contact 300—302, through winding 291 of relay 290, through the upper winding of relay 284 to the active side of battery 287. This flow of current causes the energization of relay 290, attracting its armatures to close contacts 294—295 and 296—297, contacts 293—294 and 295—296 being opened. The original flow of current, from battery 287 over the line of subscriber A, was from the grounded side of the said battery, over limb S, returning by way of limb P to the active side of the said battery. The attraction of the armatures of relay 290 reverses the direction of this flow of current, the path now being traced from the grounded side of battery 287, over limb P of the line, returning over limb S to the active side of the battery.

While the provision of means for revers-

ing the direction of the flow of current in the calling subscriber's line, upon the response of the called-for subscriber, is not essential to the operation of the system as shown, the feature is of value as rendering the system of the whole more flexible, being adapted to be used for various signaling purposes in connection with polarized electromagnets. An example of structures such as may be used in connection with the present system is shown in Fig. 5 of Patent No. 830,653 to Alfred H. Dyson, issued September 11, 1906. When at the conclusion of the conversation, either subscriber depresses keys 60 and 61 to ground the limbs of his line and replaces his receiver, the neutralizing effect of its two windings upon the core of differentially-wound relay 284 is unbalanced; armature 285 is attracted to engage anvil 286, establishing a path for the flow of current from ground at the second selector switch, Fig. 5, through the winding of release relay 175, through contact 164—162, through contact 167—165—166, contact 285—286, then joining the flow from ground through relay 276, through contact 231—228, through the winding of release magnet 232 of the connector switch, Fig. 4 to battery 189, causing the energization of release magnet 232 and release relay 175 of the second selector switch, Fig. 5. Relay 276 of the battery control circuit, Fig. 5, continues energized under these conditions. The energizations of the release magnets of the second selector switch, first selector switch and the private switch are accomplished in the same manner as described in connection with the first complete circuit diagram. When the releasing subscriber removes ground from the two limbs of his line at the substation, armature 285 of relay 284 (Fig. 5) disengages anvil 286 and opens circuit through release relay 175 of the second selector switch, Fig. 5, and release magnet 232 of the connector switch, Fig. 4, causing their deenergizations. The deenergization of release magnet 232 causes the return of the connector switch, Fig. 4, to normal; the opening of contact 231—228, caused thereby, breaks the circuit through relay 276 of the battery control circuit, Fig. 5, deenergizing it, arms 270, 273, 300 and 303 thereupon returning to normal. The returns to normal of the second selector switch, first selector switch and the private switch are accomplished as described in connection with the first complete circuit diagram.

A third complete diagram, illustrative of the circuit of my invention for providing means whereby subscribers whose lines terminate in different exchanges may automatically interconnect their lines, two conductors only being required for a trunk circuit between exchanges, comprises Fig. 2, Fig. 6, Fig. 5 and Fig. 4 placed in the order named

with Fig. 6 superposed upon Fig. 5 so that the left portion of Fig. 5 including contacts 166, 170 and 173 is covered by Fig. 6. *p* and *s* are the two limbs of a trunk circuit; the apparatus in this diagram to their left being assumed to be in one exchange, and that to their right in the second exchange. The method of operation of this circuit is similar to those already described to the point at which 10 wipers 129, 133 and 136 of the first selector switch, Fig. 2, come to rest in engagement with contacts 130, 134 and 137. Impulses corresponding to the hundreds digit of the called subscriber's number, sent by subscriber A from ground at the substation, pass through contact 135—133—134, through contact 306—307, through the winding of primary trunk relay 309, to battery 321. These four impulses of current cause 15 four attractions and releases of the armature of relay 309, each attraction and release causing an impulse of current to flow as follows: from ground at Fig. 6, through contact 313—312, through contact 348—347, over limb *p* of the trunk line, through contact 142—143, through the winding of primary relay 145 of the trunking second selector switch, Fig. 6. The four attractions and releases of the armature of relay 145, caused 20 by the above-mentioned impulses of current, cause four impulses of current to flow from ground at the second selector switch, Fig. 6, through contact 150—151, through contact 148—147, through the winding of primary 25 magnet 153 to battery 149, causing four primary movements of shaft 168 and the movement of wipers 165, 169 and 172 to positions adjacent to, but not engaging, levels of contacts, terminals of connector switches 30 assigned to the four hundreds group of the third thousand. The calling subscriber now causes one impulse of current to flow from ground at the substation, over limb *S* of the line, through contact 138—136—137, 35 through contact 318—319, through the winding of secondary trunk relay 317 to battery 321, causing the attraction and release of the armature of said relay and an impulse of current to flow from ground, through contact 313—314, through contact 351—350, over limb *s* of the trunk line, through contact 204—205, through the winding of secondary relay 207 to battery 149. The resulting 40 attraction and release of the relay's armature causes an impulse of current to flow from ground at Fig. 6, through contact 210—209, through the winding of circuit-changing switch magnet 154 to battery 149, causing the energization of the magnet and 45 the attraction of its armatures. The closing of contact 150—152 causes a flow of current from ground, through the said contact, through the winding of secondary magnet 157 to battery 149. Wipers 165, 169 and 172

move over the contacts of the before-mentioned levels, terminals of busy connector switches being grounded, as described in connection with the previous diagrams, and maintaining the circuit-changing switch magnet energized. When the wipers reach 50 contacts, terminals of an idle connector switch, circuit-changing switch magnet 154 is deenergized, opening circuit through secondary magnet 157 and preventing further movement of the wipers under the influence 55 of the said magnet. At the same time, it moves arms 162, 142 and 204 into engagement with contact points 164, 144 and 206, respectively.

The impulses sent from ground by subscriber A, corresponding to the tens digit of the called subscriber's number, cause five energizations and deenergizations of primary trunk relay 309, resulting in five impulses flowing over the following path: 60 from ground, through contact 313—312, contact 348—347, over limb *p* of the trunk line, through contact 142—144, contact 171—169—170, contact 270—271, contact 301—300, contact 184—185, through the winding of 65 primary relay 188 and to battery 189. The resulting energizations and deenergizations of relay 188 cause the operation of the connector switch as described in connection with the preceding complete diagrams. The impulse of current, sent by subscriber A from ground at the substation, over limb *S* of the line, passes through secondary trunk relay 317, over the previously traced path. The energization and deenergization of this relay 70 causes an impulse of current to flow from ground, through contact 313—314, through contact 351—350, over limb *s* of the trunk line, through contact 204—206, contact 174—172—173, contact 273—274, contact 305—303, contact 217—218, through the winding of 75 relay 221 to battery 189. Relay 221 operates the connector switch, as previously described. The four impulses corresponding to the units digit of the called subscriber's number, sent by subscriber A over limb *P* of the line, and a single impulse, following the four, sent over limb *S*, are transmitted by relays 309 and 317 of Fig. 6 to relays 188 and 221 of the connector switch, Fig. 4, over the 80 previously traced paths, causing wipers 236, 240 and 243 to engage terminals of the called subscriber's line.

Should the line be busy, the connector switch is released and subscriber A receives 85 the busy signal from busy-back machine 263, as previously described.

Should the line be idle, the engagement of arm 228 with contact 231 causes a flow 90 of current from ground at battery control circuit, Fig. 5, through relay 276, contact 231—228 and release magnet 232 to battery 189, the latter magnet not being operated 95

- thereby. The armatures of relay 276 are attracted, and arms 270, 273, 300 and 303 engage, respectively, contacts 272, 275, 302 and 304. Current thereupon flows from the 5 grounded side of battery 287, through a winding of relay 284, a winding of relay 281, through contact 293—294, through contact 275—273, through contact 173—172—174, through contact 206—204, over limb *s* of the trunk circuit, contact 350—351, contact 314—315, through the winding of relay 322, through contact 311—312, through contact 348—347, over limb *p* of the trunk line, through contact 142—144, through contact 15 171—169—170, contact 270—272, through contact 296—295, the upper winding of relay 281, the upper winding of relay 284, to the active side of battery 287. This flow of current energizes relay 322 of Fig. 6, its 20 armature being attracted to close contact 324—323. Current then flows from ground, through the said contact, through contact 327—326, through the winding of magnet 325 to the active side of battery 321. Magnet 25 325 is energized and its armature is attracted, preparing to move arms 306, 318, 347 and 350 into engagement with contacts 308, 320, 349 and 352 upon its deenergization. As the armature is attracted, it opens 30 the magnet's circuit; the armature thereupon drops back, and arms 306, 318, 347 and 350 are moved, respectively, into engagement with contact points 308, 320, 349 and 352. Pawl 21, associated with magnet 16 35 in Fig. 1, and ratchets 26 and 27 with their circuit-changing arrangement, comprises a mechanical combination that may be employed in connection with magnet 325. The closing of contacts 306—308 and 318—320 40 establishes a path for the flow of current from the grounded side of battery 328, through the lower windings of relays 329 and 334, through contact 341—340, through contact 320—318, over the talking circuit at 45 the exchange, to limb *S* of the line of substation A, through the substation, returning over limb *P*, the talking circuit, contact 306—308, through contact 337—338, through the upper windings of relays 334 and 329, 50 to the active side of battery 328. Relay 329 is differentially wound, and the magnetic effects of its two windings upon its core are balanced. Relay 334 is not differentially wound; its core is energized and attracts 55 armature 335 to engage anvil 336. Current thereupon flows from the grounded side of battery 287, through contact 275—273, through contact 173—172—174, through contact 206—204, through contact 350—352, 60 contact 335—336, through the two windings of polarized electromagnet 343 in series, through contact 349—347, through contact 142—144, contact 171—169—170, through contact 270—272, and to the active side of 65 battery 287. This flow of current is in a direction such that polarized electromagnet 343 is not actuated to cause the movement of its armature. It will be noted that the above-described flow of current traverses the windings of relays 284 and 281 (Fig. 5) 70 relay 281 attracting its armature to open contact 282—283.
- When subscriber A opens circuit, by means of key 62, through the substation to ring the called subscriber's bell, circuit is 75 broken through relay 334 of the trunk circuit, Fig. 6, and the relay is deenergized, opening contact 336—335, which interrupts the flow of current through relay 281 (Fig. 5), deenergizing the said relay and allowing 80 armature 283 to engage anvil 282. The closing of contact 283—282 closes circuit through ringing relay 288, causing it to attract its armatures and include generator 85 289 in circuit with the called subscriber's line, ringing the substation bell. When subscriber A releases key 62, closing circuit through the substation, relay 334 of Fig. 6 is again energized, its armature is attracted, closing contact 335—336, and current again flows through relay 281 (Fig. 5) 90 causing it to attract its armature and open the circuit of ringing relay 288, whose armatures return to normal.
- When the called subscriber B answers the 95 call by removing his receiver from the hook, contact 73—72 is closed, establishing a path for the flow of current from the grounded side of battery 287, through winding 292 of relay 290, over limb *S*, through the substation, returning over limb *P* and through winding 291 of relay 290, to the active side of battery 287, energizing relay 290. The 100 energization of this relay, as described in connection with the second circuit diagram, 105 reverses the connections of battery 287 to the talking circuit on the calling subscriber's side of condensers 298 and 299. In this case, the direction of the flow of current from battery 287, through the windings of polarized 110 relay 343 of Fig. 6, is reversed, the said relay is actuated, and its armature 344 attracted, closing contacts 342—340 and 339—337, and opening contacts 341—340 and 337—338. The closing of the contacts mentioned 115 reverses the direction of the flow of current from battery 328, over the line of the calling subscriber A.
- The two subscribers are now in conversation through condensers 298 and 299, over 120 limbs *p* and *s* of the trunk circuit, and through condensers 345 and 346.
- When the subscribers have finished their conversation, they depress keys 60 and 61 and replace their receivers as before. Assuming that subscriber A does this first, the 125 grounding of limb *P* of the line at the substation short circuits the lower winding of

differentially wound relay 329 (Fig. 6); while current continues to flow in equal, or greater volume, from ground at the substation, over limb S of the line, through the 5 upper winding of the said relay. This destroys the previously balanced effect of the windings upon the core of the relay, which becomes magnetized, attracting armatures 330 and 332. Their attraction establishes 10 a path for the flow of current as follows: from ground at the first selector switch, Fig. 2, through contact 128—126, contact 131—129—130, through contact 330—331 (Fig. 6), contact 333—332, through the winding of 15 relay 325 to the active side of battery 321, energizing relay 139 and relay 325.

The flow of current from ground at Fig. 2, through relay 139, after passing through contact 330—331, divides; a portion flowing 20 through contact 352—350, over limb s of the trunk line, through contact 204—206, through contact 174—172—173, through contact 273—275, through contact 294—295, through the upper winding of relay 281, 25 through the upper winding of relay 284, to the active side of battery 287. This flow of current increases the flow through the upper winding of relay 284, while the flow through the lower winding remains as before. The 30 balancing effect of the two windings upon the core of the relay is therefore destroyed; the core is magnetized and attracts armature 285 to engage anvil 286. This establishes a path for the flow of current from ground 35 at the second selector switch, Fig. 6, through the winding of its release relay 175, through contact 164—162, contact 167—165—166, through contact 285—286; the current thereupon joining the flow from ground, through 40 relay 276, flowing through contact 231—228, through the winding of release magnet 232 (Fig. 4) to battery 189. This causes the energizations of magnet 232 and relay 175, which latter attracts armature 176, causing 45 current to flow from ground at the second selector switch, Fig. 6, through contact 177—176, through the winding of release magnet 161 to battery 149.

Referring now to the first selector switch, 50 Fig. 2, the energization of release relay 139 operated to cause the energization of release magnet 125 of the first selector switch; and by also causing the energization of relay 89 of the private switch of subscriber A, caused 55 the energization of relay 66 of the said switch.

When subscriber A releases keys 60 and 61, removing ground from the line at the substation, the unbalancing effect, caused 60 by the grounding of the limbs of the line upon the core of relay 329 (Fig. 6), no longer exists. Current ceases to flow through the windings of the said relay, due to the fact that the receiver of subscriber

A has been replaced upon the hook, opening 65 contact 72—73. Armatures 330 and 332 return to normal, opening circuit through relay 325 and causing its deenergization, which effects the return of arms 306, 318 70 347 and 350 to normal. The release of the 75 said armatures also opens circuit through release relay 139 (Fig. 2) and the first selector switch and the private switch of subscriber A thereupon return to normal, as described in connection with the second complete circuit diagram.

The return of arms 347 and 350 to normal, as above mentioned, opened circuit through polarized relay 343, whose armature returns to normal, as shown in the illustration. The return of arm 350 to normal opened path for the flow of current, previously described as unbalancing the neutralizing effect of its winding upon the core of relay 284 (Fig. 5) whose armature, therefore, returns to normal, opening contact 285—286. This opens circuit through release magnet 232 of the connector switch, Fig. 4, whose deenergization causes the return of the switch to normal. The return 90 causes the deenergization of relay 276 (Fig. 5) as described in connection with the second complete circuit diagram, and arms 270, 273, 300 and 303 return to normal. The opening of contact 285—286 also effected the 95 deenergization of release relay 175 of the second selector switch, Fig. 6, whose armature thereupon disengages anvil 177, opening circuit through release magnet 161 of the 100 said switch, which thereupon returns to normal.

It will be noted that the calling subscriber, by grounding the two limbs of his line at the substation, causes the return of all apparatus, used in establishing the connection to normal.

Should subscriber B ground the two limbs of the line at his substation in advance of subscriber A, the core of relay 284 (Fig. 5) is magnetized, as described in connection with the second complete circuit diagram, which effects the energization of release relay 175 of the second selector switch, Fig. 6, and of release magnet 232 of the connector switch, Fig. 4. When subscriber B removes 115 ground from the two limbs of his line by releasing keys 60 and 61, the second selector switch, Fig. 6, the battery control circuit, Fig. 5, and the connector switch, Fig. 4, all return to normal.

The opening of contacts 142—144 and 204—206 (Fig. 6) upon the release of the second selector switch, destroys the flow of current through polarized relay 343 which is deenergized, the return of its armature reversing the direction of the flow of current from battery 328 in the line of subscriber A.

It will be noted that subscriber B, by performing the release operation, releases only the second selector switch, Fig. 6, the battery control circuit, Fig. 5, and the connector switch, Fig. 4.

The remaining apparatus, used in establishing the connection, remains to be released by subscriber A, who, by grounding the two limbs of his line, short circuits the lower winding of differentially wound relay 329 (Fig. 6), this time by the ground applied to limb S at the substation, the direction of current flowing in his line having been reversed by the deenergization of relay 343. The core of relay 329 is magnetized, armatures 330 and 332 are attracted, and the returns to normal of the private switch, Fig. 2, the first selector switch, Fig. 2, and the battery control circuit, Fig. 6, are accomplished in the same manner as that described in the case in which subscriber A performs the release operation first.

While I have shown a plurality of batteries in connection with the various circuit diagrams, it is to be understood that they may be one and the same battery. In connection with the third complete diagram, the various batteries shown may be two batteries, one of which will be located in each exchange.

The circuits, comprised in the three complete diagrams described, provide means whereby the calling subscriber is enabled to release the switches connected with his line at any stage of the operation of connecting his line with that of another subscriber. The description given in connection with the first complete diagram, explaining the manner in which the calling subscriber releases the switches upon receiving the busy signal, is typical of all of these.

The release relays, such as 175 and 139, may be slow-acting relays of which there are various types well known in the art, thus securing a prolonged impulse of current in the releasing operation.

While I have referred to the circuit at the right end of Fig. 3 as "a control circuit", I do not necessarily consider this circuit as a structure independent of the connector switch of Fig. 4, with which it is associated, but for certain purposes and due to the co-operation between them, this right end circuit of Fig. 3 may be considered as a part of the connector switch of Fig. 4.

In Fig. 7, I show the subscriber's telephonic apparatus proper, the mechanism for sending switching impulses over limbs P and S of the line, and the pay-station device including a coin slide for deposit of a coin, such deposit being necessary to place the calling device in operative relation with the line, together with polarized electromagnetic apparatus respon-

sive to current of one direction only to collect a deposited coin. Normally a coin deposited in orifice j of the coin slide, pivoted at its upper end, will descend and be returned through the lower orifice j' . When the subscriber removes his receiver, however, hook lever k ascends turning on its pivot, the downward movement of portion l shifting springs t and q to their alternate positions, the shifting of the former completing a conductive bridge of limbs P and S via key n^1 and the transmitter, while the shifting of q disconnects the condenser from the call-bell and places it in branch circuit with the receiver. The upward movement of the hook-lever operating by its pivoted member l , which is also linked to the coin slide, moves the latter to bring its lower extremity over the upper surface of armature v , so that a coin now deposited will descend and be supported by v , in which position it will press outwardly springs h and i causing them to engage their respective associate contacts. By such engagement h connects ground f with impulse springs d and c , so that the subscriber may now send the impulses over limbs P and S by rotating dial a in the direction of the arrow and then releasing it, when by its return to normal its teeth operating upon springs b and e , impulses, corresponding in number to the extent of rotation will be transmitted from f over limb P and after the last of these a single impulse will be transmitted over limb S.

The shifting of spring i on the deposit of the coin connects the windings of electromagnets r and r^1 across line limbs P and S. Magnet r is permanently polarized so that armature v is consequently held in the normal position shown, close to the magnet core.

As is well known, commercial pay station service requires that a deposited coin be returned to a subscriber in case no response is obtained by him. In applying the pay station system of Fig. 7 to the current reversing structure hereinbefore described, the arrangement would be such that the flow of current initiated when connection is first made with the called line would be in a direction to induce magnetism in magnet r to assist the permanent magnetism of the magnet, causing armature v to "stick", ordinary relay r^1 not availng then to attract armature v . While such condition exists, no answer being made, the calling subscriber may replace his receiver when member l restores the slide to normal as shown, the coin descending and returning through orifice j' . If, however, the called subscriber answers, the reversed current then flowing will, of course, being of opposite polarity, neutralize the permanent magnetism of r , r^1 will attract armature v out of supporting relation

with the coin and the latter descends and is collected in the coin box.

I do not limit myself to this employment of the reversing structure, but having described my invention, what I claim as new and desire to secure by United States Letters Patent is:

1. A telephone system including a calling subscriber's line, a substation therefor provided with a coin suspension device, a called subscriber's line, an automatic switch controlled from said calling line for extending a connection in the direction of the said called subscriber's line, a battery associated with said automatic switch having its opposite poles connected to the limbs of the calling line, means controlled by the response of the called subscriber for reversing the said connections, and means for causing said suspension device to refund or collect a coin, the said means being controlled by the direction of the flow of current in the calling line.

2. A telephone system including a calling telephone line, a pay-station device at the substation thereof, a magnet therefor controlling the disposition of a deposited coin, a called subscriber's line, an automatic switch controlled from said calling subscriber's line for extending a connection in the direction of the said called subscriber's line, a battery associated with said automatic switch having its opposite poles connected to the limbs of the calling line, and means controlled by the response of the called subscriber for reversing said connections whereby the said magnet operates to collect a deposited coin.

3. A telephone system including a calling telephone line, a pay-station device at the substation thereof, a magnet therefor controlling the disposition of a deposited coin, a called subscriber's line, an automatic switch controlled from said calling subscriber's line for extending a connection in the direction of the said called subscriber's line, a battery associated with said automatic switch having its opposite poles connected to the limbs of the calling line, means controlled by the response of the called subscriber for reversing said connections whereby the said magnet operates to collect a deposited coin, and means controlled by the replacement of the receiver at the calling substation prior to the removal of the receiver at the called substation for refunding the said coin.

4. A telephone system including a calling subscriber's line, a substation therefor provided with a coin suspension device, a called subscriber's line, an automatic switch controlled from said calling subscriber's line for extending a connection in the direction of the called subscriber's line, a battery associated with said automatic switch having

its opposite poles connected to the limbs of the calling line, means controlled by the response of the called subscriber for reversing said connections, and means controlled by said reversed flow of current for causing said coin suspension device to collect a coin.

5. A telephone system including a calling subscriber's line, a substation therefor provided with a coin suspension device, a called subscriber's line, an automatic switch controlled from said calling subscriber's line for extending a connection in the direction of the called subscriber's line, a battery associated with said automatic switch having its opposite poles connected to the limbs of the calling line, means controlled by the response of the called subscriber for reversing said connections, means controlled by said reversed flow of current for causing said coin suspension device to collect a coin, and means controlled by the replacement of the receiver at the calling substation prior to the removal of the receiver at the called substation for returning said coin.

6. A telephone system including a calling subscriber's line, a substation therefor provided with a coin collecting device, a called subscriber's line, an automatic switch for connecting said calling subscriber's line to said called subscriber's line, a battery associated with said switch having its opposite poles connected to the limbs of the calling subscriber's line, and means for reversing said connections thereby causing said coin device to collect a deposited coin.

7. A telephone system including a calling subscriber's telephone line, a coin suspension device associated with said line, a called subscriber's line, automatic trunking means for connecting said calling subscriber's line to said called subscriber's line, a battery associated with said trunking means having its opposite poles connected to the limbs of the calling line, means for reversing the said connections whereby said coin suspension device operates to collect a deposited coin.

8. A telephone system including a calling telephone line, a pay station device at the substation thereof, a polarized magnet therefor for controlling the disposition of a deposited coin, a called subscriber's line, automatic trunking means for connecting said calling subscriber's line to said called subscriber's line, a battery associated with said trunking means having its opposite poles connected to the limbs of the calling line, and means controlled by the response of the called subscriber for reversing said connections thereby causing said magnet to collect a deposited coin.

9. A telephone system including a calling subscriber's line, a substation thereon provided with a coin suspension device, a called subscriber's line, automatic trunking means

for connecting said lines in conversational circuit, a battery associated with said trunking means having its opposite poles connected to the limbs of the calling line, means 5 for reversing said connections thereby causing a deposited coin to be collected, and means controlled by the replacement of the receiver at the calling substation prior to the reversal of current over the calling line 10 for refunding the said coin.

10. A telephone system including a calling subscriber's telephone line, a substation thereon provided with a token suspension device, a called subscriber's line, electromagnetically controlled automatic means for connecting said lines in conversational circuit, a battery associated with said automatic means having its opposite poles connected to the limbs of the calling line, and 15 means for reversing said connections thereby causing said token suspension device to deposit a suspended token.

11. A telephone system including a calling subscriber's telephone line, a substation thereon provided with a token suspension device, a called subscriber's line, electromagnetically controlled automatic means for connecting said lines in conversational circuit, a battery associated with said automatic means having its opposite poles connected to the limbs of the calling line, means for reversing said connections thereby causing said token suspension device to deposit a suspended token, and means controlled by 25 the replacement of the receiver at the calling substation prior to the reversal of said connections for causing said token suspension device to return said token.

12. A telephone system including a calling subscriber's telephone line, a substation thereon provided with a token suspension device, a called subscriber's line, electromagnetically controlled automatic means for connecting said lines in conversational circuit, a battery associated with said automatic means having its opposite poles connected to the limbs of the calling line, and means controlled by the response of the called subscriber for reversing said connections thereby causing said token suspension device to collect a deposited token.

13. A telephone system including a calling subscriber's telephone line, a substation thereon provided with a token suspension device, a called subscriber's line, electromagnetically controlled automatic means for connecting said lines in conversational circuit, a battery associated with said automatic means having its opposite poles connected to the limbs of the calling line, means controlled by the response of the called subscriber for reversing said connections thereby causing said token suspension de-

vice to collect a deposited token, and substation controlled means actuated prior to 65 the reversal of said connections for refunding said token.

14. A telephone system including a calling subscriber's telephone line, a substation thereon provided with a token suspension device, a called subscriber's line, electromagnetically controlled automatic means for connecting said lines in conversational circuit, a battery associated with said automatic means having its opposite poles connected to the limbs of the calling line, and means controlled over the called subscriber's 70 line for reversing said connections thereby operating said token suspension device to collect a deposited token. 80

15. A telephone system including a calling subscriber's telephone line, a substation thereon provided with a token suspension device, a called subscriber's line, electromagnetically controlled automatic means for 85 connecting said lines in conversational circuit, a battery associated with said automatic means having its opposite poles connected to the limbs of the calling line, means controlled over the called subscriber's 90 line for reversing said connections thereby operating said token suspension device to collect a deposited token, and means controlled at the calling substation prior to the reversal of such connections for refunding 95 the suspended token.

16. A telephone system including a calling line, a check operated device having means sensitive to current in a particular direction over said line, a battery and connections to place the same across said line, means for reversing said connections for purposes of said device, said means having a circuit controlled by the electrical condition of an engaged called line test contact. 100 105

17. A telephone system including a calling line, a check operated device therefor, a source of current adapted to have its opposed terminals connected to said line, a connector to connect with the called line, 110 apparatus to reverse the connections of said source to the calling line for purposes of said device, and means dependent upon the electrical condition of a called line test contact engaged by said connector to control the 115 connections of said apparatus.

18. A telephone system comprising a built-up connection between a calling and called line, including numerically adjustable automatic switching means, a central 120 source of current in series with the calling line, means for reversing the polarity of said source with respect to the said line, and a token receiving device for the calling line having means sensitive to such reversal. 125

19. A telephone system including numerical automatic switch means for building up a connection from the calling toward the called line, a path for the flow of current in series over the limbs of the calling line, apparatus including a contact of said switch means whereby a switch at the called substation serves to reverse the direction of such flow, and a token receiving device having a member moved in response to the reversal. 65
20. A telephone system including a source of current in series with a calling line's limbs, a called line, and a directly adjusted automatic switch in the connection between said lines, means controlled at the called station for reversing the direction of current in the calling line, a token device sensitive to the reversal, a side switch magnet adapted when its armature falls back to shift its contacts to final position whereby circuit changes are controlled placing said reversing means under control of the called line, and busy test circuit means for the called line preventing such shifting if the called line is busy. 70
21. A telephone system including numerical automatic electrical switch means for building up a connection from the calling toward the called line, a path for the flow of current in series over the calling line limbs, apparatus controlled from the called line to reverse the direction of such flow, a token receiving device having a winding sensitive to such reversal, contacts adapted to be operated to place said reversing means under control of the called line when it is idle, and means for preventing such operation of the contacts if the called line is busy. 75
22. A telephone system comprising a built-up connection between a calling and a called line, including numerically adjustable electric switch means, a central source of current in series with the calling line, means for reversing the polarity of said source to said line, said means being controlled over the called line, a token receiving device having apparatus sensitive to such reversal, a called line contact, means for rendering it busy, an electromagnet adapted to receive current via contact only in case said contact is busy, and means responsive to such current to prevent placing said reversing means under control of the called line. 80
23. A telephone system including a calling line and a central battery normally in series connection with it, automatic means responsive to control at the substation of said line for substituting a second series connection of said source with said line for the first, and placing said second under control of the called subscriber, whereby the response of the called subscriber reverses the poles of said source to the calling line, and a token receiving device having means actuated by such reversal. 85
24. A telephone system including a calling subscriber's telephone line, a substation thereon provided with a token suspension device, a called subscriber's line, electromagnetically controlled automatic means for connecting said lines in conversational circuit, a device at the calling substation for controlling said electromagnetically controlled automatic means, said device being inoperative to control said automatic means until a token is deposited in said suspension device, a battery associated with said automatic means having its opposite poles connected to the limbs of the calling line, and means controlled by the response of the called subscriber for reversing said connections thereby causing said token suspension device to collect a deposited token. 90
25. A telephone system including a calling telephone line, a pay station device at the substation thereof, a magnet therefor controlling the disposition of a deposited coin, a called subscriber's line, an automatic switch controlled from said calling subscriber's line for extending a connection in the direction of the said called subscriber's line, said automatic switch being non-controllable over said calling subscriber's line until a coin is deposited in said pay station device, a battery associated with said automatic switch having its opposite poles connected to the limbs of the calling line, and means controlled by the response of the called subscriber for reversing said connections whereby the said magnet operates to collect a deposited coin. 95
26. A telephone system including a calling subscriber's line, a substation therefor provided with a coin suspension device, a called subscriber's line, an automatic switch controlled from said calling subscriber's line by a calling device thereat for extending a connection in the direction of the called subscriber's line, said calling device being inoperative to control said automatic switch until a coin is deposited in said coin suspension device, a battery associated with said automatic switch having its opposite poles connected to the limbs of the calling line, means controlled by the response of the called subscriber for reversing said connections, and means controlled by said reversed flow of current for causing said coin suspension device to collect a coin. 100
27. A telephone system including a calling subscriber's telephone line, a substation thereon provided with a token suspension device and a calling device, a called subscriber's line, electromagnetically controlled automatic means controllable by said calling device for connecting said lines in con- 105

- versational circuit, said calling device being inoperative to control said automatic means until a token is deposited in said suspension device, a battery associated with 5 said automatic means having its opposite poles connected to the limbs of the calling line, and means for reversing said connections thereby causing said token suspension device to deposit a suspended token.
- 10 28. A telephone system including a calling subscriber's telephone line and a called subscriber's telephone line, a token suspension device located at the substation of said calling subscriber's line, a link circuit for 15 use in connecting said calling subscriber's line to said called subscriber's line, automatic means for said link circuit responsive to the idle condition of the called subscriber's line for associating said calling subscriber's line with said called subscriber's line, a battery for said link circuit having its opposite poles connected to the limbs of 20 the calling line, and means for reversing the said connections whereby said coin suspension device operates to collect a deposited token. 25
29. A telephone system including a calling subscriber's telephone line, a substation therefor provided with a token suspension device, a called subscriber's line, a link circuit for use in extending a connection from said calling subscriber's line to said called subscriber's line, automatic means for testing the called subscriber's line to determine whether or not the said calling subscriber's line will be operatively associated with said called subscriber's line, a battery having 30 its opposite poles connected to the limbs of the calling line, and means for reversing said connection thereby causing the said token suspension device to deposit a suspended token. 35
